PIPE BENDING ASSEMBLAGE

Edward M. Pfauser, Elm Grove, Wis., assignor to
Blackhawk Mfg. Co., Milwaukee, Wis., a corpora-
tion of Wisconsin

Application November 27, 1939, Serial No. 306,239

2 Claims. (Cl. 153—38)

The present invention relates in general to improvements in the art of laterally distorting elongated structural or tubular elements, and relates more specifically to various improvements in the construction and operation of portable assemblages for bending pipes, tubes, I-beams, angle beams, channel beams, or the like.

A general object of my present invention is to provide an improved bending assemblage for elongated bodies which is simple and durable in construction, and which is moreover readily manipulable and highly effective in use.

Some of the more important specific objects of my invention are as follows:

To provide improved pipe or beam bending or straightening mechanism which is conveniently and efficiently operable with the aid of a fluid pressure actuated jack such as a hydraulic ram.

To provide a new and useful pipe distorting assemblage which can be quickly applied to relatively inaccessible pipes or beams and which may be actuated from a more accessible remote point or station.

To provide an improved portable tool for bending or straightening tubular or beam-like elongated elements such as pipes or structural beams, which is light but sturdy in construction and can be conveniently transported from place to place.

To provide an improved mechanism for laterally distorting elongated objects, and which will most effectively cooperate with such objects having various cross-sections and diameters.

To provide an improved pipe or beam bender, or the like, which is operable in any desired direction, and which will work the same regardless of its position.

To provide an improved mounting for tube and pipe bending machines or the like, whereby the unit may be rolled along the ground.

To provide an improved pipe bending attachment for power jacks, various parts of which are readily adjustable to perform different operations and to most effectively cooperate with conduits of large and small diameter.

To provide an improved bender for rod-like elements, which requires no special tools for operation thereof and for adjustment of its parts.

To provide a pipe bending assemblage which can be quickly applied to or removed from a standard jack or hydraulic ram, which may be safely operated by a novice, and which will not dent the pipes.

To provide improved reaction blocks and block mountings for a pipe bender assemblage or the

like, and also an improved plunger head cooperative with the blocks.

To provide various other improvements in the construction of pipe benders or the like whereby the cost of manufacture thereof is minimized and the efficiency is enhanced.

These and other specific objects and advantages of my present invention will be apparent from the following detailed description.

10 A clear conception of an embodiment of the invention, and of the mode of constructing and of utilizing pipe bending assemblages made in accordance with the improvement, may be had by referring to the drawing accompanying and forming a part of this specification wherein like reference characters designate the same or similar parts in the various views.

Fig. 1 is a side perspective view of one of my improved pipe bending attachments associated with a hydraulic power system comprising a ram and a pump for delivering liquid from a supply reservoir to the ram;

20 Fig. 2 is an enlarged perspective view of the bending attachment and ram of Fig. 1, looking toward the pipe engaging and transporting elements;

25 Fig. 3 is a further enlarged transverse section taken through one of the pipe engaging corner blocks; and

30 Fig. 4 is a part sectional side elevation of one of my improved corner blocks mounted upon its supporting pin.

While I have shown the invention applied specifically to a portable and hydraulically actuated assemblage which has been designated as a pipe bender, it is not the intent to thereby unnecessarily restrict the scope or utility of the improvement; and the hydraulic system specifically shown and only partially described herein, 35 is of the type disclosed in my Patent No. 2,165,504, granted July 11, 1939, wherein the hydraulic ram has a cylinder and a plunger both provided with screw threads at their corresponding ends, co-operable with threaded sockets or openings in 40 detachable tool elements.

Referring to the drawing, my improved pipe bending assemblage comprises in general an approximately triangular rigid frame 8 having laterally spaced similar opposite side plates 9 permanently and firmly attached to a ram mounting block 10 at the apex of the triangle, and also having two series of aligned holes 11 near the triangle base but extending away from the adjacent corners and toward a central point remote from the base line; a ram 12 having an outer cylinder

element 13 one end of which is detachably secured as by screw threads to a central bore 14 piercing the frame block 10, and also having an inner plunger element movable longitudinally within the cylinder element 13; a pipe engaging head or saddle 15 detachably secured as by screw threads to the outer end of the ram plunger element and being movable between the frame side plates 9; and a pair of similar rotatably adjustable pipe engaging corner blocks 16 of special construction, 10 each carried by a supporting pin 17 cooperable with a selected set of aligned holes 11 of the two inclined series.

The triangular bender frame 8 may be constructed either as separate pieces which may 15 be welded or otherwise rigidly united, or the side plates 9 may be formed integral with the block 10; and the plates 9 are preferably disposed parallel to each other and should be sufficiently thick to withstand the enormous pressures to which 20 they may be subjected. The side plates 9 may also be provided with local lugs 18 of sufficient height to prevent damage to or displacement of the pins 17 when the frame 8 is allowed to rest on its side; and the holes 11 of the two oppositely inclined series may be provided with identifying marks or numerals 19 as shown in Fig. 2, which designate the proper location of the pins 17 when bending pipes of different diameters. The disposition of the holes 11 for cooperation with various size pipes, is important, in order to produce most effective lateral bending of the pipes without denting or deforming the circular cross sections.

The hydraulic ram 12 with which the improved attachment is detachably associative, should preferably be readily controllable and operable from a remote point, and this may be accomplished with a jack or ram system such as shown in Fig. 1. The displacement chamber within the 35 cylinder 13 of the ram 12 is connected by means of a flexible conduit 20 with a pump 21 having a liquid supply reservoir 22 associated directly therewith, and the pump 21 is manually operable with the aid of a lever 23. As previously 40 indicated, the ram 12, pump 21, reservoir 22, and connecting conduit 20 may be of the type shown in my Patent No. 2,165,504; and the frame 8 and saddle 15 which are relatively movable by the hydraulic ram 12, may be detachably 45 but firmly secured to the ram cylinder 13 and to the ram plunger, respectively, by means of screw threads formed concentric with the ram axis. It is noteworthy that the use of a hydraulic ram 12, rather than a mechanical jack operable by screw threads, will always cause the frame 8 and saddle 15 to move relatively to each other only along the axis of the ram 12 and without tending to rotate the saddle relative to the frame about this axis.

The pipe engaging head or saddle 15 which is detachably connected by screw threads to the ram plunger, has a longitudinally and laterally curved pipe engaging recess 24, and may be externally reinforced by ribs 25. In order to prevent distortion of the transverse cross-section of a pipe, during lateral bending thereof, the transverse curvature of the saddle recess 24 should at least approximately conform with the external curvature of the pipe. It is therefore desirable to provide as many different saddles 15 as there are sets of holes 11 provided in the side plates 9 of the triangular frame 8. For example in the assemblage shown in Fig. 2, the pipe engaging corner blocks 16

are mounted concentrically of the holes 11 corresponding to operation on a 4 inch tube or pipe, and the recess 24 of the saddle 15 should in this case correspond in transverse curvature, 5 approximately with the transverse external curvature of a 4 inch pipe. If the spaced blocks 16 are shifted to cooperate with the holes 11 marked 2, then the saddle 15 should be replaced by one having a recess 24 properly curved to coat with the exterior of a 2 inch pipe. The sets of holes 11 which are nearest each other, may be utilized to bend both 1½ and 1¼ inch pipes, but different blocks 16 having properly curved recesses should then be used.

The corner blocks 16 are furnished in sets adapted to properly coat with tubes and beams of different shapes and sizes, and one type of these rotatably adjustable pipe engaging corner blocks 16 and their mountings, is shown in detail in Figs. 3 and 4. Each set of these blocks 16 by virtue of the special construction and mounting thereof, may be utilized to bend tubes and beams of various external diameters and shapes. As shown, each of the blocks 16 has four curved recesses 26 all having different curvature, but the bottoms of all of which are disposed equidistant from the axis of the block 16. The transverse curvatures of the recesses 26 are such that the recess surfaces will approximately fit pipes of the diameters designated by the numerals 19 at the holes 11; and by inclining the series of holes 11 toward the jack cylinder 13, no loss of stroke of the ram plunger results in contacting pipes of different diameters. Another set of blocks 16 adapted to fit other sizes of pipes, may also be provided, and one of the recesses 26 may be omitted on each block 16 in favor of a flat surface adapted to coat with flat surfaces of beams such as angle bars, I-beams or channel beams.

Each block 16 is bored centrally to snugly engage its carrier pin 17, and is provided with end hubs 21 which fit snugly between the side plates 9 of the frame 8. The removable block supporting pins 17 are also of like and interchangeable construction, and each of these pins 17 has a manipulating handle 28 at one end and a taper 29 at its opposite end, and the frame lugs 18 preferably extend outwardly beyond the pin tapers 29. Each pin 17 is moreover provided with a stop ring 30 for limiting its travel during insertion of the pin; and also has a friction ball 31 confined in a socket thereof and urged outwardly by a spring 32, so as to retain the pin 17 in place. The pins 17 are readily insertible within and removable from the holes 11 of the frame 8 and the central bores of the blocks 16, and these blocks may be rotated about the pin axes so as to bring any selected set of grooves 26 into operative relation with the saddle 15. In order to permit the pipe bending assemblage to be readily transported, I also provide circular disks 33 either coating with the hubs 21 or formed integral with the blocks 16, and these disks 33 serve as transporting wheels in the manner shown in Fig. 1.

During normal use of the improved pipe bending assemblage, the ram cylinder 13 should first be attached to the frame block 10 at the threaded opening 14, so that the frame 8 will be rigidly attached to the ram 12. The operator should then select the bending shoe or saddle 15 which will properly fit the pipe which is to be laterally distorted, and the selected saddle 15 should then be attached to the plunger of the ram 12 which

is provided with screw threads for that purpose. The pipe to be bent should then be placed inside of the frame 8 between the side plates 9, in contact with the groove 24 of the saddle 15, while the jack plunger is fully withdrawn or retracted. The pivot blocks 16 should then be positioned with the aid of the pins 17, in the proper sets of alined holes 11, and the blocks 16 should be rotated to cause the proper grooves 26 thereof to face the previously inserted pipe. The release valve of the pump 21 should then be closed and by manipulating the handle 23, liquid from the reservoir 22 may be forced by the pump 21 through the pipe 20 into the displacement chamber of the ram cylinder 13. This admission of liquid under pressure will cause the saddle 15 to move outwardly and to force the pipe into engagement with the spaced blocks 16. Continued application of pressure to the ram plunger will cause the pipe to bend, and as the bending proceeds the blocks 16 will rotate slightly about the axes of the pins 17. By this procedure bends of 90 degrees may be produced in pipes of various sizes, and when a bend has been completed, the release valve of the pump 21 may be operated so as to retract the plunger and the saddle 15 associated therewith. The bent pipe may then be either withdrawn endwise from within the frame 8, or the blocks 16 may be removed and the pipe bender may thereafter be withdrawn laterally from the pipe.

From the foregoing detailed description it will be apparent that my present invention provides an improved pipe bending assemblage which is simple and durable in construction and which may be readily manipulated from a point remote from the bending assemblage. The use of a hydraulic ram for operating the pipe bending elements is especially advantageous, since it permits the application of great force without tending to rotate the saddle 15 about the jack axis. The saddle 15 is, however, free to rotate about this axis so as to cause the same to automatically align itself with the pipe or object being operated upon. The improved construction of the reaction block 16 with the grooves 26 spaced equidistance from the block axis, provides a strong block construction capable of resisting enormous pressures. The mounting for the blocks 16 also permits ready removal and insertion thereof with respect to the various sets of holes 11, and the inclined disposition of the series of holes 11 permits most effective bending of pipes having various diameters without loss of stroke of the ram plunger. The rigid frame 8 is also extremely desirable since it maintains the corner blocks 16 in any fixed predetermined position with respect to the ram 12, and insures formation of perfect bends. The transportation disks 33 do not interfere with the normal adjustment of the blocks 16, but greatly facilitate transportation of the unit from place to place, and the entire assemblage may obviously be furnished to the trade in neatly packed condition in boxes or chests. The various parts of the assemblage are readily adjustable to perform the definite operations desired, most effectively, and the mechanism will obviously cooperate with various types of elongated bodies such as tubes, flat or cylindrical bars, structural beams of various cross-sections, and other bodies hav-

ing sizes within the range of operation of the tool. The improved pipe bender has proven highly successful in actual commercial use, and can be manufactured and sold at extremely moderate cost.

It should be understood that it is not intended to limit this invention to the exact details of construction or to the precise mode of use, herein shown and described, for various modifications may occur to persons skilled in the art, and the term "pipe" as used herein is intended to cover any elongated object whether tubular or solid, and regardless of its cross-sectional size or shape.

I claim:

1. A pipe bending assemblage comprising, a small portable ram having a cylinder and a plunger movable within the cylinder both provided with externally screw threaded corresponding ends, flexible conduit means for delivering fluid under pressure to said cylinder to move said plunger while permitting universal movement of the ram, a frame having a hub provided with internal screw threads adapted for attachment to said cylinder end threads and being provided with integral approximately parallel and triangular side plates each having series of holes extending toward the corners thereof remote from said hub, parallel pins cooperable with selected alined holes of said side plates, a pipe engaging block rotatably supported by each of said pins and having integral parallel circular opposite side flanges separated by an annular series of pipe contacting grooves of different curvature all spaced equi-distant from the axis of the corresponding supporting pin, and a pipe bending saddle movable outwardly between said blocks by said ram and having internal screw threads adapted for attachment to said plunger end threads, the entire assemblage being invertible and transportable while utilizing said circular block flanges as supporting wheels and said ram as a handle.

2. A pipe bending assemblage comprising, a small portable ram having a cylinder and a plunger movable within the cylinder both provided with screw threaded corresponding ends, flexible conduit means for delivering fluid under pressure to said cylinder to move said plunger while permitting universal movement of the ram, a frame having a hub provided with screw threads adapted for attachment to said cylinder end threads and being provided with integral approximately parallel and triangular side plates each having series of holes extending toward the corners thereof remote from said hub, parallel pins cooperable with selected alined holes of said side plates, a pipe engaging block rotatably supported by each of said pins and having plane parallel circular opposite side flanges widely separated and located on the opposite sides of an annular series of pipe contacting grooves of different curvature adapted to coact with pipes of different diameters, and a pipe bending saddle movable outwardly between said blocks by said ram and having screw threads adapted for attachment to said plunger end threads, the entire assemblage being invertible and transportable while utilizing said circular block flanges as supporting wheels and said ram as a handle.

EDWARD M. PFAUSER.
